UNITED STATES PATENT OFFICE.

BENSON BIDWELL, OF PHILADELPHIA, PENNSYLVANIA, ASSIGNOR OF ONE-HALF TO CHARLES F. BIDWELL, OF INDIANAPOLIS, INDIANA.

ELECTRIC RAILWAY.

SPECIFICATION forming part of Letters Patent No. 684,596, dated October 15, 1901.

Application filed August 14, 1884. Serial No. 140,514. (No model.)

To all whom it may concern:

Be it known that I, BENSON BIDWELL, a citizen of the United States, residing at Philadelphia, in the county of Philadelphia and State 5 of Pennsylvania, have invented certain new and useful Improvements in Electric Railways, of which the following is a specification, reference being had therein to the accompanying drawings, wherein—

10 Figure 1 is a transverse vertical section of a car and railway equipped with my improvements. Fig. 2 is a longitudinal broken section of the same. Fig. 3 is an end view, partly sectional, of a tubular conductor and a contact brush or wheel. Fig. 4 is a side view, partly in section, of the brush or wheel. Fig. 15 5 is an end view showing attachment of the conductors to the longitudinal sleepers or bed-rail for the tracks. Fig. 6 is a like view illustrating such attachment to the guard-rail for 20 the tracks. Fig. 7 is a horizontal section of the conductor-switch or movable section. Fig. 25 8 is a plan showing the application of such switch to a system of railways equipped with the tubular line conductors. Fig. 9 is a section of two crossing lines of conductors, illustrating their construction at the crossing to 30 permit the contact-brushes to pass by the same; and Fig. 10 is a broken plan of such crossing conductors.

My invention has relation to electric railways of that form having slotted tubular conductors for the line-current or that form shown and described in an application filed 35 by me on the 16th day of February, A. D. 1884, Serial No. 122,123, which application was divided and formed the basis for Patents No. 305,730, dated September 23, 1884; No. 315,113, dated April 7, 1885; No. 504,549, 40 dated September 5, 1893, and No. 318,594, dated May 26, 1885. It has for its object to provide a system of supports for the line conductors whereby they may be economically applied to elevated or other railways now constructed, and any section of which conductors can be readily removed or displaced for 45 repairs, substitution, or for other purposes; to provide traveling roller or wheel contact-brushes which have an inherent or automatic 50 vertical movement or upward pressure and are

also capable of a lateral motion whereby they automatically maintain their contact with the line conductors when the car vibrates vertically or sways to and fro laterally; to provide for reversing the direction of travel of the car; 55 to utilize the electric motor on the car for a brake mechanism; to provide a circuit changing or reversing switch for said electric motor, which switch also serves as an ordinary make-and-break switch for the motor-circuit; to provide for mechanically switching the contact-brushes to and from a main line to sidings or branch lines to electric conductors, and, finally, to provide crossing lines of conductors so arranged that the contact-brushes of each 60 65 can pass by the crossing conductors without necessitating unshipping of the brushes from the conductors.

My invention accordingly consists of the combination, construction, and arrangement 70 of parts, as hereinafter described and claimed, having reference particularly, first, to slotted tubular conductors composed of pipe-sections so connected to the longitudinal sleepers or bed-rails of the tracks that the ends of 75 the sections electrically contact, yet each section is independent of its neighbor, whereby it may be easily unshipped; to a contact-roller or wheel-brush having a spring or elastic bearing and a hinged or pivoted connection 80 with its supporting-arm attached to the car or train; to a car having an electric motor and a circuit changing or reversing switch, which is adapted to serve also for an ordinary make-and-break switch; to line conductors having jointed or switch sections adjoining and connected to the track-switch rails, and to crossing lines of conductors, one of which is broken or mutilated, but electrically connected at the crossing. 85

In the drawings, A represents the tracks or line of way of an elevated or other railroad, and B B the tubular conductors for the line-current or that generated by any suitable form of dynamo-electric machine C, located at 90 a station along the line of way. Said conductors form a closed metallic circuit for the generator and have longitudinal slots b arranged as shown or as described in my aforesaid application. These conductors are made 95 100

up of pipe-sections, each end of all the sections being screwed to or otherwise provided with brackets or supports b' . The ends of the sections preferably project through the 5 brackets b' , so that when the latter are secured to the longitudinal track-rails a the adjoining ends of two pipe-sections will abut against each other and provide a continuous electrical contact for the conductor-sections. 10 As a further means for insuring such continuity of contact each pair of brackets b' throughout the line are electrically connected by a twisted wire or other suitable circuit connections. (Shown at b^2 .) If desired, the 15 brackets b' may be insulated from the rails a by plates of rubber or other non-conducting material b^3 . The conductors B being made up of sections and each section having independent supports or brackets b' , any one of 20 the sections is capable of being displaced for repairs or otherwise without necessitating removal of adjoining sections. Instead of securing the brackets to the rails or sleepers a , as shown more plainly in Fig. 5, they may 25 be fastened to the guard-rail A' when used as indicated in Fig. 6, or they may be attached to the cross-ties. These modes of attachment for the conductors avoid the use of separate poles or other supports for the conductors. 30 Consequently railroads already constructed may be economically equipped with my improvements.

C' indicates a car having depending arms c for carrying the contact-brushes D . Each of 35 said brushes is composed of a roller or wheel d , journaled in the end of an upright bar d' , the lower end of which enters an opening e in a socket E . Said bar is loosely held in said socket by a cross-pin d^2 , which passes through 40 elongated vertical side slots e^2 in the socket, a play-space e^3 being provided between the lower end of bar d' and the bottom of socket-opening e to permit bar d' to move up and down or have a vertical motion. Between 45 the socket E and a shoulder d^3 on bar d' and surrounding the latter is a spiral spring E' , the tendency of which is to raise the bar d' and its wheel d or give to them an upward or outward pressure to positively maintain electrical contact with the inner surface or bore 50 of the conductor, into which they are inserted and along which they travel. The expansive force of spring E' also keeps the brush or wheel d in contact with the conductor as 55 the car vertically vibrates. The bracket E is pivoted or loosely connected at e^3 to its carrying-arm c , and such pivotal connection is arranged at right angles to the axis of the contact brush or wheel d , so that during a 60 lateral motion or swaying of the car the contact brush or wheel will also yield laterally to still keep itself in impingement with the conductors to preserve the electrical contact therewith. Such lateral movement of the 65 brush is indicated by dotted lines z , Fig. 3. A brush so constructed, therefore, is automatically moved or pressed upwardly or out-

wardly and has a lateral motion to effectually keep it in contact with its conductor under varying conditions of travel.

70

Upon the car is located a suitable electric motor F , which has an extended length of armature-shaft f , on each end of which is mounted a gear or pinion f' . The latter meshes into driving-gear f^2 , secured to or 75 formed, as shown, on the inner sides of the car-wheels G . The axle g of the latter and the armature-shaft are connected or braced by links g' , which support and maintain the armature-shaft f in line with axle g .

80

H represents a circuit changing or reversing switch, composed of two levers h h , pivoted at h' and connected to an insulated handle h^3 , and of two pairs of contact-points or electrodes h^2 and h^4 . The pivots of the levers and the electrodes h^2 h^4 are in circuit with the field-magnets and armature of the motor and with the contact-brushes or their arms c , as shown, or otherwise, as desired, so that by alternately making contact with the electrodes h^2 and h^4 the direction of the line-circuit through the motor is changed or the poles of the latter reversed. The reversal of the poles of the motor changes the direction of rotation of its armature, which in turn reverses the direction of travel of the car. As the reversal of motion of the armature takes place slowly or against pressure and the weight of the car previously moving in an opposite direction, such motion serves as a 100 simple and effective brake for stopping the car. By moving the levers h h of switch H midway between each pair of the electrodes or out of contact with all of them the motor is cut out of the line-circuit. It will be noted, 105 therefore, that switch H is not only a reversing-switch, but is also a common make-and-break switch, and it, together with the motor, forms the braking mechanism for stopping the car.

110

In Fig. 8 I have shown my improvements applied to a railway and its branches or to a system of railways, in which case the conductor-sections B' , adjacent to the switch-rails A^2 of tracks A , are connected at one end 115 by a ball-and-socket or other swivel joint b^5 , and their opposite ends are free. These sections are suitably connected to the rails A^2 , as shown at m , so as to move therewith. By such construction I obtain a conductor-switch 120 B^2 for connecting the main-line conductors to a branch or reversely to switch the contact-brushes from one line to another without requiring their removal from the conductors. The electrical continuity of the main and 125 branch lines of conductors during such switching is maintained by means of spring or elastic conductors $m' m'$ or spring-fingers m^2 .

130

In Figs. 9 and 10 I have illustrated cross-lines of conductors arranged to permit the contact-brushes of each line conductor to pass by the crossing without necessitating unshipping of same. In this case one of the lines of conductors is broken or section of the same

removed at the crossing, and the crossing conductors are located one above the other. The ends of the severed conductors are electrically connected by wires *n*, which pass under the lower crossing conductors to be out of the way of the moving brushes. The latter in this case consists of elongated bars *D'*, having the contact-wheels *d* at each end thereof, and the spring *E'* and pivoted bar *E* at the center of same, so that one end of the brush will span the space between the severed conductor ends and enter one of the latter before leaving the other and thereby preserve the electric circuit for the car-motor. The brushes in the lower crossing tubes are as first above described. By such construction of crossing conductors and of brushes the latter are free to pass by crossing lines of conductors without requiring removal therefrom or breaking the circuit for the motors on the cars. The ends of the broken conductors at the crossing are preferably expanded, as shown at *N*, for guiding the contact-wheels into the conductors.

25 I do not confine myself to the particular construction of the spring-supported contact-brushes, the conductor, switches, and other novel features herein shown and described, as it is evident that each of them may be variously constructed without departing from the spirit of my invention.

Having thus described my invention, what I claim as new, and desire to secure by Letters Patent, is—

35 1. In an electric railway, the conductors *B* composed of sections, with separate supporting-brackets for each said section, and connecting circuits or wires at the junction of said sections.

40 2. In an electric railway, the line and side or branch tracks, and switch-rails at the junction of said line and branch tracks, main and branch slotted tubular electric conductors, and movable or switch slotted tubular con-

45 ductors at the junction of the main and branch conductors and secured and moving with the track-switch rails.

3. In an electric railway, the sectional conductors, supporting-brackets therefor, circuits located in juxtaposition to the sections of the conductors, insulation for said sup-

porting-brackets, traveling current-collectors comprising L-shaped depending bars, vertical bars provided with sockets and pivotally secured to the L-shaped bar, brushes or roller-rods vertically sliding and located in the sockets of the vertical bars, springs encircling the vertical bars, and a roller pivotally secured in the top of the vertical bar. 55

4. In an electric railway, the sectional conductors, supporting-brackets therefor, circuits located in juxtaposition to the sections of the conductors, insulation for said supporting-brackets, traveling current-collectors comprising L-shaped depending bars, vertical bars provided with sockets and pivotally secured to the L-shaped bar, brushes or roller-rods vertically sliding and located in the sockets of the vertical bars, springs encircling the vertical bars, and a roller pivotally secured to the top of the vertical bar, brackets *b'* secured to the track-rails, the ends of the sectional conductors projecting through said bracket, whereby the conductor-sections abut against each other and form a 75 continuous electrical contact for the conductor-sections.

5. In an electric railway, the sectional conductors, supporting-brackets therefor, circuits located in juxtaposition to the sections of the conductors, insulation for said supporting-brackets, traveling current-collectors comprising L-shaped depending bars, vertical bars provided with sockets and pivotally secured to the L-shaped bar, brushes or roller-rods vertically sliding and located in the sockets of the vertical bars, springs encircling the vertical bars, and a roller pivotally secured in the top of the vertical bar, brackets *b'* secured to the track-rails, the ends of the sectional conductors projecting through brackets, of the independently-supported sectional conductors, whereby any one of the sections may be removed without removing the other or adjoining section. 90 95

In testimony whereof I affix my signature in presence of two witnesses.

BENSON BIDWELL.
